UNITED STATES PATENT OFFICE.

MAX OERTZ, OF HAMBURG, GERMANY.

SHIP'S RUDDER.

Application filed August 1, 1924. Serial No. 729,606.

To all whom it may concern:

Be it known that I, Dr. Ing. MAX OERTZ, engineer, a citizen of the German State, 84 An der Alster, Hamburg, Germany, have 5 invented certain new and useful Improvements in Ships' Rudders, of which the following is a specification.

The new rudder for ships is in two parts. It consists of a rigid leading body, and of 10 a rudder body arranged in the rear hollow thereof, broadened and sharply diverging in front. The two together have a shape conforming as closely as possible to the shape of the supporting plane of a flying 15 machine, particularly when the rudder is arranged at a distance from the hull of the ship.

The invention is based upon the relationship between the lengths of the two parts 20 of the rudder and upon the correct utilization thereby attainable of the supporting plane form for the purpose of the most favourable steering effect with the smallest possible expenditure of power.

25 The broadened leading body overlapping the rudder body in front is comparatively short in the longitudinal direction of the ship. The movable rudder body is longer. When arranging the two-part rudder at a 30 distance from the hull of the ship the articulation between the two lies somewhere about the position of maximum convexity. The length of the leading body is to the length of the rudder body about as 1:2.

35 The new cutwater-shaped rudder produces an effect immediately in consequence of this construction, even in the case of the smallest rudder position. In any position of the rudder the augmented convexity of 40 the rudder at the pivot position is always located in such a way as is most favourable for the steering effect.

The new rudder is illustrated in the accompanying drawings,

45 In Figure 1 in cross section, with a slight rudder position shown dotted.

Figure 2 shows by way of example how the invention can easily be constructed in sheet iron.

To the stationary headpiece *a*, which is 50 at the same time the rudder port and the leading body for the rudder the rear rudder body *c* is pivoted about the axis *b*. The head piece consists according to Figure 2 of a sufficiently strong iron plate parabolic in 55 section, the open part of which is closed and rendered fluidtight by a sunk wall. The rearwardly extending projections of the wall of the leading body overlap the forward convex part of the rudder body *c*, 60 which is likewise made out of sufficiently strong sheet iron and closed.

What I claim is:—

1. A ship's rudder consisting of a rigid leading member spaced from the body of 65 the ship and having a convex front and a hollow at the rear, a rudder body longer than the leading member, having a convex and relatively broad front and tapering to a point at the rear, rotatably arranged in 70 said hollow and articulated to said leading member, the side walls of the hollow of said leading member overlapping in front of said rudder body.

2. A ship's rudder consisting of a rigid 75 leading member parabolic in cross-section arranged at a distance from the main body of the ship, said leading member including a rear wall arranged forwardly of the rear edges of the parabolic portions to provide 80 a hollow, and a tapering rudder body pivoted to said leading member and having a convex front edge partially lying within the hollow of the leading member, said leading member and said rudder body having 85 a substantially continuous and uninterrupted external surface.

3. A ship's rudder as claimed in claim 1 characterized in that the leading member and rudder body present a substantially continuous and uninterrupted external surface. 90

In testimony whereof I affix my signature in presence of two witnesses.

DR. ING. MAX OERTZ.

Witnesses:

N. KASPAUH,
E. HÖPF.
